UNITED STATES PATENT OFFICE.

CARLTON NEWMAN, OF SAN FRANCISCO, CALIFORNIA.

FRUIT-JAR.

SPECIFICATION forming part of Letters Patent No. 320,580, dated June 23, 1885.

Application filed March 16, 1885. (No model.)

To all whom it may concern:

Be it known that I, CARLTON NEWMAN, of the city and county of San Francisco, State of California, have invented an Improvement 5 in Fruit-Jars; and I hereby declare the following to be a full, clear, and exact description of the same.

My invention relates to the class of fruit-jars, and to a new and useful means for fastening and holding the lid or cover to its seat. 10 My invention consists of a bail passing over the top of the cover or lid, and bearing directly on its center, and a screw-band encircling the neck of the jar and connected with 15 the ends of the bail, as I shall hereinafter fully explain.

The object of my invention is to provide a simple, effective, and economical fastening for the lids of jars.

20 Referring to the accompanying drawings for a more complete explanation of my invention, Figure 1 is a perspective view of my fruit-jar. Fig. 2 is a vertical section of the upper portion of the same. Fig. 3 is a perspective view of the screw-band and bail.

25 A is the jar, and B its lid. Around the neck a of the jar are formed screw-threads a'.

C is a band or ring internally threaded and adapted to fit the threads a' of the neck.

30 D is a bail the ends of which are firmly secured to the ring or band C. The center of the bail is bent downwardly and bears upon the center of lid B.

35 By screwing the ring C down the bail is carried down and caused to press on the center of the lid, thus tightening and binding it to its seat. The reverse movement of the ring relieves the lid. This central bearing which is brought upon the lid is better, in that it is 40 more equal, than a bearing brought upon and throughout the circumference of the lid, as is usually done. There is no tendency to tip the lid by reason of an unequal pressure.

45 The fastening I have described is simpler and cheaper than the ordinary screw-sleeve, whose inwardly-turned top flange binds on the edge of the lid, because in the manufacture of these sleeves great care must be taken to true their flanges to produce an even bearing, and also more material is used in stamp-

ing out the sleeves than in forming rings, such as C. I am aware that fastenings have been made by means of a centrally-bearing bail, the ends of which are bent to form hooks, engaging inclined lugs or planes on the neck of the jar; but the disadvantage of this fastening lies in the tendency of the bail (which is made of wire) to bend or twist under the strain of setting it up, thereby disengaging its hooks from the lugs. The resisting power of the 60 hooks is, moreover, small, both because of their size and the small bearing they find, and finally the bail is rather difficult to handle in setting it up. All these disadvantages are overcome by combining the bail with the screw-band. I obtain the central pressure, and at the same time have a great resisting power, 65 on account of the large bearing and engaging surface of the ring or band to which the bail is attached. There is no tendency to slip, and the ring is easily grasped to set the bail to its position.

I am aware that fastenings are old in which a coil of wire encircles the threaded neck of the jar and to which bails are secured, the top 75 centers of which bear upon the center of the cover or lid, whereby it is secured. I do not therefore claim such broadly, but confine myself to the solid annular band of metal internally threaded, which is adapted to fit the 80 neck of the jar and to bind the bail upon the cover.

Having thus described my invention, what I claim as new, and desire to secure by Letters Patent, is—

85 A fastening for binding the lid or cover of a jar to its seat, comprising the solid metal band or ring C, internally threaded and adapted to fit upon an externally-threaded neck of the jar, and the bail D, bearing on the center 90 of the lid and having its ends secured to the metal band or ring, substantially as herein described.

In witness whereof I have hereunto set my hand.

CARLTON NEWMAN.
